UNITED STATES PATENT OFFICE.

MARY EVA NORTHEN, OF DENTON, TEXAS.

PATTERN-CHART.

SPECIFICATION forming part of Letters Patent No. 761,901, dated June 7, 1904.

Application filed September 2, 1903. Serial No. 171,635. (No model.)

To all whom it may concern:

Be it known that I, MARY EVA NORTHEN, a citizen of the United States, residing at Denton, in the county of Denton and State of Texas, 5 have invented a new and useful Pattern-Chart, of which the following is a specification.

This invention relates to pattern-charts for cutting garments for men, women, and children; and it consists particularly in certain improvements upon the system of pattern-charts 10 patented to me August 25, 1885, by Letters Patent No. 325,216.

In describing the invention reference will be had to the accompanying drawings, forming 15 part of this specification, in which there is exhibited a complete set of pattern-charts constructed in accordance with this invention, the novel features of which will be fully pointed out in the appended claim.

20 In the drawings, Figure 1 is a view showing the front-waist rule, which also shows the curves for use in cutting pants. Fig. 2 shows the back-rule. Fig. 3 shows the sleeve-rule. Fig. 4 shows a combined dart-rule and skirt-rule. Fig. 5 shows the extra-dart rule. Fig. 25 6 shows the pants-leg rule. Fig. 7 shows the pants-rule and waistband-rule.

The several rules illustrated are respectively formed and marked with perforations, 30 lines, and figures, as represented in the drawings, and when prepared for sale and practical use will bear printed upon the surface thereof directions as full as need be for using the several rules in the cutting of a great variety of garments.

Any suitable sheet material which is not apt to become distorted from use may be used in the manufacture of the charts. The preferred material, however, is a heavy card-board 40 which possesses sufficient flexibility to permit folding in order to reduce the charts to small compass and which is of sufficient weight to facilitate the ruling of patterns along the margins thereof.

45 The front-waist rule (shown in Fig. 1) has the straight frontedge a , on which are marked the scales P , the front R point, and a portion of the $R R$ back-scale, which extends onto the

neck-curve b . The remainder of the margin of the front-waist rule is made up of the compound shoulder-curve c , the armhole-curve d , the compound back-curve e , and the bottom curve f , along which are formed the scales O and $O O$. At a slight distance from the straight front edge a is the bust-measure scale 50 A , which is just below the neck-curve. In alignment with the scale A and near the bottom of the rule is a substantially similar scale I . Between the scale A and the $R R$ back-scale is the front R scale. (Indicated by dot-and-dash lines and perforations.

The scale by which the contour of the neck-opening is determined is the scale B , lying adjacent to the scale A and the upper part of the front R scale. The obliquely-disposed 65 scale C and the more obliquely disposed scale D are used in determining the shoulder-curve, and the scale D is used in connection with the scale E and the scale F in determining the outline of the armhole. The rear margin of 70 the front waist-piece is determined by means of the scale F , the oblique scale G , and the waist-measure scale T , which is disposed horizontally between scales F and G .

It will be noted that scales F and T are 75 double scales, the portions near the rear edge of the front-waist rule being provided for plotting the outline of women's garments, and the portions nearer the forward margin being used in cutting patterns for children's garments.

Point 1^H and point 4^H are used in connection with scales 2^H , 3^H , 5^H , and 6^H in determining the size of the darts in women's garments when two darts are employed in each front 85 waist-piece, the outlines of the darts being determined by the concave side of the combined skirt and dart rule. (Shown in Fig. 4.)

When only a single dart is desired in each front-waist piece, as in making coats and 90 loose-fitting waists, the point J is used in connection with the scales J^2 and J^3 .

The length of waist is plotted by the scale U , which, together with the scale T , makes up the large perforated area in the lower rear 95 corner of the front-waist rule.

The ordinary form of skirt-dart is marked by the perforations shown at S. The scales indicated by dot-and-dash lines at K, L, M, X, Y, and at Z are used in connection with the outline-curves connecting those scales and the front R and back R scales for cutting the upper portions of pants-pieces, the lower portions of which are cut by the pants-rule illustrated in Fig. 6.

10 The back-rule (illustrated in Fig. 2) has the straight edge *g*, the concavely-curved top *h*, the oblique margin *I*, the rear armhole-curve *k*, the side margin *l*, and the straight bottom *m*. Scales A' B' C' D' E' F' G' H' I' T' U' correspond generally in position to scales A, B, C, D, E, F, G, H, I, T, and U on the front-waist rule and are similarly used.

15 The sleeve-rule (illustrated in Fig. 3) has the curved sides *n* and *p*, the curved top *o*, and the straight bottom *r*. The scales A'' and A'' along the margin *n* are used plotting the forward edges of the sleeve-pieces. The scales B'' and F'' are used in determining the length of the rear margin of the sleeve-pieces, the curves of which will be drawn by the margin *p*. The scale E'' on the margin *o* is used in determining the starting-point for forming the upper curve of the outer half of the dress-sleeve, and the scale E'' E'' is used in determining the upper curve of the inner half of the dress-sleeve.

20 The combined skirt and dart rule (shown in Fig. 4) has the point *s* and the differently-curved sides *t* and *t'*, the former of which is used, as already stated, in ruling the outlines of darts and the latter of which is employed in ruling the convex edge for back and side form. The combined skirt and dart rule is also provided with a plurality of transverse 25 lines at A⁴ and B⁴ for determining the lengths of collar-pieces, the outline of which may be ruled by either edge of the combined skirt and dart rule. The lengths for the collar-pieces are determined from the bust-measure, and in 30 order to make the collar-pieces of proper length it is only necessary, the bust-measure being known, to mark the length from the line A⁴ to that one of the lines at B⁴ which bears the number corresponding to the bust-measure.

35 40 45 50 55 60 The extra-dart rule is formed with the point *u* and the differently-curved sides *v* and *w*, is perforated at C⁵ D⁵ E⁵ and is provided with the transverse lines A⁵ B⁵, for laying off the lengths of collars, the bust-measure being known. In laying off collars from the scales shown on the extra-dart rule the lines corresponding to the bust-measure in each of the groups A⁵ and B⁵ should be noted, and the inner margin of the collar may be ruled along the edge *w*. The outside margin may be made of any desired configuration.

The pants-legs chart (illustrated in Fig. 6) is

formed with the slightly-curved margin M', and the more sharply curved margin N' is marked with scales—front L⁶, back L⁶, back U⁶, and the scale V⁶. The use of the pants-leg chart in connection with the front-waist rule and the dot-and-dash scales and diagrams thereon is indicated in the dot-and-dash diagram shown at the upper end of the pants-leg chart. It is to be understood that the lines shown in the drawings of this specification as dot-and-dash lines will in the practical construction of the charts be shown, preferably, as red lines to avoid any possibility of confusion.

10 The pants-rule and waistband (illustrated in Fig. 6) is graduated throughout its length in inches and is provided along the curve at the upper end with a small scale for use in connection with the R, L, and X scales on the waist-rule.

15 In order to cut patterns by this chart, the measurements necessary for the waist-pieces, front and back, are the bust-measure, length of waist in center of back, and circumference of waist. For sleeves the length of the inside of the arm and the width around the band at its widest part are required in addition to the bust-measure. For pants the waistband, 20 length of inside seam, and bust-measure (used as hip-measure) are required.

25 The outlines of the charts are so drafted that by means of the measurements above mentioned garments to fit persons of figures approaching the average in symmetry may be 30 cut very successfully by persons of comparatively small skill in cutting, and by measuring the length of waist under the arm and down the center of the front irregular forms 35 may be fitted correctly.

40 Among the special advantages possessed by the improved chart may be mentioned the single-dart scales and point upon the front-waist rule; the R R back-scale, which is used 45 in the cutting of pants to correct the length of the outside seam and to secure a proper fit at the back; the E'' E'' sleeve-scale, by which 50 the curve of the under seam of the sleeve is perfected; the A'' A'' sleeve-scale for shaping 55 the inner sleeve-seam and preventing its twisting onto the top of the arm, and the collar-scales upon the dart-rules, by means of 60 which accurately-fitting collars may be cut when the bust-measure is known.

65 Having thus described the construction and advantages of my invention, what I claim as new, and desire to secure by Letters Patent, is—

70 In a system of pattern-charts, a front-waist rule and a pants-rule having points adapted to register to bring the two rules into position for use at the same time in cutting a single piece of fabric, said pants-rule being pro-

vided with transverse rulings forming a scale, and the front-waist rule being provided near the upper forward corner thereof with a scale for use in connection with a scale formed on the pants-rule for determining the length of the outside seam of the pants.

5 In testimony that I claim the foregoing as

my own I have hereto affixed my signature in the presence of two witnesses.

MARY EVA NORTHEN.
